DAVID WILCOX, OF BOSTON, MASSACHUSETTS, ASSIGNOR TO HIMSELF, W. H. SLOCUM, AND W. A. BROWN, OF SAME PLACE.

Letters Patent No. 91,189, dated June 8, 1869.

IMPROVEMENT IN HATS.

The Schedule referred to in these Letters Patent and making part of the same.

To all whom it may concern:

Be it known that I, DAVID WILCOX, of Boston, in the county of Suffolk, and State of Massachusetts, have invented certain new and useful Improvements in the Method of Making Hats; and I do hereby declare that the following is a full and exact description thereof, reference being had to the accompanying drawings, and to the letters of reference marked thereon.

The nature of my invention consists in so forming the hat-body that that part of the crown next to the rim may be folded upon or within itself in such a manner that the hat will appear to have a band, and that part which comes in immediate contact with the head will be treble in thickness, thus preventing, to a considerable degree, the perspiration from working through to the outside.

To enable others skilled in the art to make and use my invention, I will proceed to describe its construction and use.

Drawings.

Figure 1 is a perspective view of my hat.

Figure 2 is a section, showing the hat with the upper part folded within.

Figure 3 is a section of the same, showing the upper part folded outside.

Construction.

The hat-body is made in the usual manner, and of any desired material, size, and style, and, while soft and pliable, it is folded and pressed, either as represented in fig. 2 or in fig. 3, and is then subjected to the usual finishing-processes.

If desirable, the folds H I C D may be stitched or cemented together.

Having thus described my invention, I will proceed to set forth my claim,

What I claim as my invention, and desire to secure by Letters Patent of the United States, is—

A hat, whose body is shaped into folds H I C D, substantially as described, and for the purpose set forth.

DAVID WILCOX.
